US0D1064918S

(12) **United States Design Patent** (10) **Patent No.:** **US D1,064,918 S**
(45) **Date of Patent:** **** Mar. 4, 2025**

(54) **UNMANNED AERIAL VEHICLE**

(71) Applicant: **IONA Logistics Ltd.**, Cranfield (GB)

(72) Inventor: **Saif-Deen Akanni**, Parma (IT)

(73) Assignee: **IONA Logistics Ltd.**, Cranfield (GB)

(**) Term: **15 Years**

(21) Appl. No.: **29/899,465**

(22) Filed: **Aug. 9, 2023**

(30) **Foreign Application Priority Data**

Feb. 9, 2023 (GB) 6261293

(51) **LOC (15) Cl.** **12-06**

(52) **U.S. Cl.**

USPC **D12/16.1**
